UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

ELECTRIC SIGNALING SYSTEM.

1,296,097.

Specification of Letters Patent.

Patented Mar. 4, 1919.

Application filed December 22, 1915. Serial No. 68,208.

To all whom it may concern:

Be it known that I, ALBEN E. LUNDELL, a citizen of the United States, residing at New York, in the county of Bronx and State of New York, have invented certain new and useful Improvements in Electric Signaling Systems, of which the following is a full, clear, concise, and exact description.

This invention relates to signaling systems, and more particularly to systems in which variably operable electromagnetic mechanisms control the actuation of desired signals.

It is the object of this invention to provide new and improved arrangements for actuating a plurality of signals designating digits, without the necessity of actuating signals which would not change the value of the desired numerical signal.

The drawing represents diagrammatically a signaling system, only so much being shown of the circuits and mechanisms as is necessary for a clear understanding of this invention.

Under the control of a sender, registering switches 10, 11 and 12 and a sequence switch 13 may be set to control the operation of lamp signals 14, 15, 16, 17 and 18 respectively. The lamps and contacts shown between vertical dotted lines above the registering and sequence switches, are controlled by said switches respectively. Register 10 may be adjusted in accordance with the 100's, register 11 the 10's, and register 12 the units dig-

ital numeral of the desired signal. The lamps which are grouped in the same manner as the registers, will be actuated thus to display the desired number. The resting positions of the registers are indicated by letters and numerals.

The operation of registering and sequence switches, and of senders, is well-known in the art, and such devices of widely varying character may be used for practising the present invention without departing from the spirit of the same. A complete description of a preferred form of such apparatus may be had from my Patent No. 1,168,319, of January 8, 1916, filed August 22, 1913.

After the sender has been adjusted for controlling the operation of registers 10, 11 and 12, an impulse controlling circuit is closed from ground through contact 20, the winding of a stepping magnet 21 and the

winding of a relay 22 to grounded battery. 55 Relay 22 becomes energized and closes a circuit from ground through its front contact and bottom armature, contact 23 of sequence switch 13, conductor 24 and the power magnet of the 100's register 10 to grounded battery. Under the control of a normal spring 25, register 10 is moved out of its N position. In each half position of register 10, i. e., while the register is moving between the positions indicated adjacent to spring 25, a 60 ground impulse is sent through contact 26, conductor 27 to magnet 21, and the establishment of this connection causes the short-circuiting of magnet 21. Upon the deenergization of magnet 21, the adjusted sender is 65 stepped in the well-known manner toward its normal position. Supposing that the sender has been set to cause the signaling lamps to indicate numeral 101; the first closure of contact 26 will cause magnet 21 to 70 step the sender into its zero position, and as the originally traced circuit for register 10 is still closed in this position, this register is caused to move out of its 0 position and cause in position 0½ to send another im- 75 pulse to magnet 21, whereupon this magnet 80 will step the sender into its normal position.

The impulses representing the first digit having been sent out, contact 20 is opened, 85 whereupon relay 22 becomes deenergized. A circuit is closed now from ground through the upper back contact and armature of this relay, contact 30 of register 12, contact 31 of register 11, contact 32 of register 10, conductor 33, sequence switch contact 34, conductor 35, and the power magnet of sequence switch 13 to grounded battery. Under the control of normal spring 36, sequence switch 13 is caused to move out of position 1 into 90 position 2.

Contact 20 is again closed and relay 22 becomes again energized and establishes a circuit from ground through its bottom front contact and armature, sequence switch 100 contact 37, conductor 38 and the power magnet of the 10's register 11 to grounded battery. Under the control of normal spring 39, this register is moved out of its N position. When moving through position N½, 105 register 11 causes, in the same manner as has been described in connection with register 10, the restoration of the sender by closing

its contact 40. The sender, having been set to actuate the signal indicating zero, is now restored to its normal position and the impulse controlling circuit is opened at contact 20. Register 11 remains in its X position. Upon the deenergization of relay 22, circuit is closed from ground through the upper back contact and armature of relay 22, contact 30 of register 12, contact 41 of register 11, sequence switch contact 42, conductor 35 and the power magnet of sequence switch 13 to grounded battery, for moving this switch out of position 2 into position 3.

Contact 20 having been closed after the sending out of the 10's impulses, relay 22 again becomes energized and causes the closure of a circuit from ground through its bottom front contact and armature, sequence switch spring 43 and the power magnet of register 12 to grounded battery, whereby, under the control of normal spring 44, this register is moved out of position N. In each half position of this register a short-circuiting impulse is sent through contact 45 to magnet 21, causing this magnet to step the sender until register 12 reaches position 1. The impulse sending circuit is now constantly open at contact 20. Relay 22 becomes deenergized and closes a circuit from ground through its upper back contact and armature, contact 46 of register 12, sequence switch contact 34, conductor 35, and the power magnet of sequence switch 13 to grounded battery, for moving this switch out of position 3 into position 6.

When register 12 reaches position 0, a circuit is closed from ground through register contacts 47, 48 and 49, and through the winding of register 11 to grounded battery, whereby this register is moved out of position X into position 0. Registers 10, 11 and 12 being in positions 1, 0 and 1 respectively, and sequence switch 13 in position 6, a circuit is closed from ground through sequence switch contact 50, conductor 51, register contacts 52, 53 and 54, and lamps 14, 15 and 18 in parallel to grounded battery, for lighting these lamps, designating numeral 101.

If the 100's digit is zero, lamp 55 will not be actuated as contact 56 of the 100's register is constantly open.

Let us suppose that the operator controlling the sender sets up the numeral 001. In the previously described case, although the 10's digit was zero, lamp 15 was actuated, as the zero digit in that case was of numerical importance. In this case, however, the indication of the zero 10's digit is superfluous.

As the 100's register was left in position zero, and the 10's register was driven out of position N into position X, in response to the operation of the sender, there will be no circuit established upon the setting of register 12 through contacts 47, 48 and 49 for

register 11, and therefore this register will remain in its X position, in which the lamp 15 will not be lighted.

After the displaying of the desired number, the operator, to whom this signal was conveyed, depresses a key 60, causing thereby the closure of a circuit from ground through this key, sequence switch contact 61, conductor 35 and the power magnet of sequence switch 13 to grounded battery, for moving sequence switch 13 out of position 6 into position 16. The lamps are extinguished upon the opening of contact 50. In position 16, a circuit is closed from ground through the contacts of sequence switch spring 62 and through the register contacts 63, 64 and 65, for moving the registers out of their actuated position into their N position. A circuit is now closed from ground through the upper back contact and armature of relay 22, register contacts 30, 31, 32 and 33, conductor 67, sequence switch contact 68, conductor 85 and the power magnet of sequence switch 13, for moving this switch out of position 16 into position 1.

What is claimed is:

1. In combination, a plurality of electromagnetic mechanisms, a device for controlling the operation of said mechanisms normally disconnected therefrom, means for successively connecting said mechanisms with said device, a controlling circuit for one of said mechanisms, contacts in said circuit controlled by a mechanism, and contacts in said circuit controlled by another mechanism arranged to be connected to said device subsequent to the connection of said one of said mechanisms.

2. In combination, a plurality of electromagnetic mechanisms, a device for controlling the operation of said mechanisms normally disconnected therefrom, means for successively connecting said mechanisms with said device, a controlling circuit for one of said mechanisms, contacts in said circuit controlled by a mechanism arranged to be connected to said device previous to the connection of said one of said mechanisms, and contacts in said circuit controlled by another mechanism arranged to be connected to said circuit subsequent to the connection of said one of said mechanisms.

3. In combination, a plurality of electromagnetic mechanisms, a device for controlling the operation of said mechanisms normally disconnected therefrom, means for successively connecting said mechanisms with said device, a controlling circuit for one of said mechanisms, contacts in said circuit controlled by said one of said mechanisms, contacts in said circuit controlled by a mechanism arranged to be connected to said device previous to the connection of said one of said mechanisms, and contacts in said circuit controlled by another mechanism ar-

ranged to be connected to said circuit subsequent to the connection of said one of said mechanisms.

4. In a signaling system, a plurality of signals representing a plurality of groups of digits, an electromagnetic mechanism for controlling the signals of each group, a device for controlling the adjustment of said mechanisms in accordance with any numerical designation of the desired signals, and means for preventing the actuation of the desired signal representing a certain numeral of the second digit.

5. In a signaling system, a plurality of signals representing a plurality of groups of digits, an electromagnetic mechanism for controlling the signals of each group, a device for controlling the adjustment of said mechanisms in accordance with any numerical designation of the desired signals, and means controlled by the mechanism of the first group of signals for preventing the actuation of a signal representing a certain numeral of the second digit.

6. In a signaling system, a plurality of signals representing a plurality of groups of digits, an electromagnetic mechanism

for controlling the signals of each group, a device for controlling the adjustment of said mechanism in accordance with the numerical designation of the desired signals, and means jointly controlled by the mechanisms of the first and third group of signals for preventing the actuation of a signal representing a certain numeral of the second digit.

7. In combination a plurality of signals representing two groups of digits, an electromagnetic mechanism for controlling the signals of each group, a sender for adjusting said mechanisms in accordance with the numerical designation of the desired signals, means for actuating the desired signal of the second group if the desired signal of the first group represented a digit other than zero, and means for preventing the actuation of the signal representing a desired zero numeral of the second digit, if the desired first digit was zero.

In witness whereof, I hereunto subscribe my name this 18th day of December A. D., 1915.

ALBEN E. LUNDELL.
